BRACKET FOR REMOTE CONTROL UNITS

David C. Rockola, Chicago, Ill., assignor, by mesne assignments, to Rock-Ola Manufacturing Corporation, Chicago, Ill., a corporation of Delaware

Application February 20, 1947, Serial No. 729,793

6 Claims. (Cl. 248—226)

1

This invention relates in general to supporting structures, and more particularly to a bracket for supporting a remote control unit for an automatic phonograph on a counter, bar, or the like.

A principal object of the invention is to provide a bracket for supporting a remote control unit of an automatic phonograph on a horizontally disposed shelf-like member, such as a bar or counter, without marring, marking or otherwise disfiguring the shelf-like member.

Another important object of the invention is the provision of a two part supporting bracket having the two parts thereof readily adjustable relative to each other to clamp the bracket on shelves, counters or bars of different thicknesses, and means for rigidly securing the one part to the other in any such desired adjusted position.

A further object of the invention is the provision of such a supporting bracket in which means are incorporated for adjusting the two parts thereof relative to each other which are readily accessible for operation but are enclosed within the bracket so as not to detract from the appearance of the bracket and also to eliminate sharp corners and protuberances upon which clothing and the like could catch or snag.

Numerous other objects and advantages of the invention will be apparent as it is better understood from the following description, which, when taken in connection with the accompanying drawings, discloses a preferred embodiment thereof.

In the drawings:

Figure 1 is a top plan view of a bracket embodying the instant invention;

Fig. 2 is a side elevation of the bracket of Fig. 1 mounted on a shelf-like member, which, together with a remote control unit supported by the bracket, are shown in broken lines;

Fig. 3 is a rear elevational view of the bracket, as seen from the left of Figs. 1 and 2; and

Fig. 4 is a horizontal section taken substantially on the line 4—4 of Fig. 2.

Referring more particularly to Fig. 2 of the drawings, a remote control unit 11 for an automatic phonograph is illustrated in broken lines therein which may be similar to those disclosed and designated by reference character F in United States Letters Patent No. 2,389,327 issued November 20, 1945 to D. C. Rockola, et al. The present invention provides a novel bracket, indicated generally by reference numeral 12, for mounting such a control unit, or the like, on a shelf-like member 13, such as a bar or counter.

The bracket 12 comprises a right-angled frame member having a vertical portion or leg 14 terminating at its lower end in a forwardly extending (to the right in Figs. 1 and 2) horizontal portion or leg 15 adapted to engage the under surface of the shelf 13, and a horizontally disposed clamp member 16 slidably mounted at

2

its rear end on the vertical leg 14 and adapted to engage the upper surface of the shelf 13. The frame member 14, 15 is preferably formed as a unitary metal stamping, and includes a centrally disposed reinforcing channel portion 17 displaced rearwardly from the main plane of the vertical leg 14 and continuing below the horizontal leg 15 as a similar reinforcing channel 18. The lower end of the channel portion 17 at its intersection with channel 18 has an indentation or recess 19 formed therein to provide a horizontally disposed shoulder 21. This shoulder 21 has an aperture 22 therein (Fig. 2) through which the body portion of an adjusting bolt 23 extends, the head of this bolt being adapted to contact against the shoulder 21.

The rear end of the horizontal clamping member 16 is provided with an extension 24 disposed within the channel 17, which is provided with a suitable vertically disposed, tapped aperture for receiving the thread portion of the bolt 23. The horizontal clamping member 16 is also provided with a pair of laterally extending ears or lugs 25 adjacent the rear end thereof, the rear surfaces of which slidably engage the front surface of the vertical leg 14. The leg 14, as best seen in Fig. 3, has a pair of vertically disposed slots 26 adjacent the sides thereof through which bolts 27 extend, these bolts being screwed into suitable tapped apertures in the lugs 25.

With the arrangement above described, rotation of the bolt 23 will result in vertical adjustment of the clamping member 16 relative to the horizontal leg 15 of the bracket. Such adjustable movements of the clamping member 16 enable attachment of the bracket 12 to shelves 13 of different thicknesses. When once adjusted in this manner so that the shelf 13 is tightly clamped between the member 16 and the lower leg 15, tightening of the bolts 27 will rigidly secure the clamping member 16 to the vertical leg 14 to maintain the bracket in such mounted position. In this manner, the bracket 12 is adapted to be rigidly mounted upon a shelf-like member comprising a counter or bar without scratching, marring or otherwise disfiguring the finished surfaces thereof. If desired, however, the bracket 12 may be additionally secured to the shelf 13 by means of wood screws (not shown). Such screws may extend through the slots 26 into the rear edge portion of the shelf 13, or upwardly into the shelf through apertures provided in the horizontal leg 15 by downward bending of suitable tabs 28 (Figs. 1 and 2) partially punched through the leg portion 15 of the bracket.

The vertical leg 14 of the bracket, as best shown in Fig. 3, is provided with three vertically disposed slots 29 in the upper portion thereof for receiving bolts 31 adapted to be screwed into suitable tapped apertures in a back plate 32 shown in broken lines. This plate 32 in turn is secured

to the remote control unit 11 in any suitable manner to mount the latter upon the bracket 12.

From the above description, it will be apparent that the bracket 12 is adapted to mount a remote control unit, or the like, on a horizontally disposed shelf, such as a counter or bar, without marring the finish of the latter. At the same time, because of the smooth contours given the bracket 12 and the fact that the adjusting bolt 23 is housed within the channel 17, clothing or the like cannot be caught or snagged on the bracket. Nevertheless, the adjusting bolt 23 may be operated with facility to move the member 16 into clamping position, and subsequent tightening of the bolts 27 is sufficient to rigidly maintain the bracket on the bar or counter.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A bracket for supporting an automatic phonograph remote control unit on shelf-like members of different thicknesses, comprising a vertical frame member attachable to said remote control unit and having a forwardly extending horizontal portion adapted to engage the lower surface of a said shelf-like member, a horizontal member mounted at its rear end on said vertical frame member for free vertical sliding movement relative thereto and extending forwardly therefrom to engage the upper surface of said shelf-like member, means spaced from said shelf-like member for adjustably interconnecting said horizontal member and said vertical frame member to effect sliding movement of the horizontal member relative to the vertical frame member to clamp said shelf-like member between the horizontal portion of the latter and said horizontal member, and means for rigidly securing said horizontal member to said vertical frame member in any adjusted position.

2. In combination with a remote control unit for an automatic phonograph, a structure for supporting said unit above a horizontal shelf, comprising a backing plate secured to said unit, a frame member having a vertical leg secured to said backing plate and a horizontal leg engageable with the under surface of said shelf, said vertical leg having a centrally disposed reinforcing channel portion extending rearwardly from the main body portion thereof, a horizontal clamping member slidably mounted at its rear end on said vertical leg and extending forwardly therefrom for engagement with the top surface of said shelf, means disposed within said channel portion for adjusting said clamping member vertically relative to said horizontal leg and means interconnecting said vertical leg and the rear end of said horizontal clamping member to guide adjusting movements of the latter relative to said horizontal leg.

3. A device of the class described, comprising a right-angled frame member, a clamping member slidably mounted on one portion of said frame member for movement relative to the other portion of said frame member disposed at right angles to said first portion, means interconnecting said members and operable to slidably adjust the relative positions thereof to effect a clamping

action, and means for rigidly securing said clamping member to said frame member in any adjusted position.

5. In a device of the class described, a frame member having a vertical leg with a centrally disposed reinforcing channel portion displaced rearwardly from the main plane thereof and a horizontal leg extending forwardly from the lower end of said vertical leg, said channel portion being recessed at its lower end to provide an apertured horizontal shoulder disposed rearwardly of said horizontal leg, a horizontal clamping member slidably mounted at its rear end on said vertical leg and having an extension disposed in said channel portion with a vertical tapped aperture therethrough, and a bolt extending upwardly through the aperture in said horizontal shoulder and said channel portion into threaded engagement with said tapped aperture, with the head thereof engaging said shoulder, for adjusting said clamping member vertically relative to said horizontal leg.

6. In a device of the class described, a frame member having a vertical leg with a centrally-dis-

25 posed reinforcing channel portion displaced rearwardly from the main plane thereof and a horizontal leg extending forwardly from the lower end of said vertical leg, said channel portion being recessed at its lower end to provide an apertured horizontal shoulder disposed rearwardly of said horizontal leg, a horizontal clamping member slidably mounted at its rear end on said vertical leg and having an extension disposed in said channel portion with a vertical tapped aperture

30 therethrough, a bolt extending upwardly through the aperture in said horizontal shoulder and said channel portion into threaded engagement with said tapped aperture, with the head thereof engaging said shoulder, for adjusting said clamping member vertically relative to said horizontal leg,

35 and means for rigidly securing said clamping member to said vertical leg in any adjusted position.

40 7. In a device of the class described, a frame member comprising a vertical leg with vertical slots adjacent its side edges and a centrally-dis-

45 posed reinforcing channel displaced rearwardly from the main plane thereof, and a horizontal leg extending forwardly from the lower end of said vertical leg, a horizontal clamping member abutting the forward surface of said vertical leg with its rear end and having a rearward extension dis-

50 posed in said channel, adjusting means extending upwardly through said channel and engaging said extension for adjusting the vertical position of said clamping member relative to said horizontal leg, and bolts extending through said slots and

55 engaging said clamping member for rigidly securing the latter to said vertical leg in any adjusted position.
